UNITED STATES PATENT OFFICE

HARVEY C. HAYES, OF WASHINGTON, DISTRICT OF COLUMBIA

SOUND RECEIVER

Application filed August 17, 1927. Serial No. 213,632.

(GRANTED UNDER THE ACT OF MARCH 3, 1883, AS AMENDED APRIL 30, 1928; 370 O. G. 757)

This invention relates primarily to improvements in devices for converting sound or similar waves into electrical effects. More particularly it is the purpose of the invention to provide an improved form of magneto-electric device of the type commonly termed a magnetophone for transforming a mechanical impulse into an electric current or change in an already existing current.

Heretofore it has been the common practice to employ devices of the microphone type for the purpose of detecting sounds, particularly where the impulses are relatively feeble. Devices of this character are more sensitive than other devices which might be employed but they are not uniform or reliable in their action. When it is desired to match receivers, as required for binaural reception, it is impractical to employ microphones since even if once matched they will not remain in this condition for any length of time.

The present invention contemplates a form of magnetophone which is accurate and reliable in its action and which is of sufficient sensitivity to adapt it for the reception of relatively feeble sound or similar waves.

An important consideration in the development of the present novel devices was the need for eliminating as far as possible the usual restoring forces acting upon the armature or other movable part of a magneto-electric device tending to prevent its displacement. It will be apparent that when the restoring forces are relatively large the sensitivity of the instrument is necessarily low.

By the present invention the restoring forces tending to oppose the displacement of certain of the parts under the influence of a sound receiving diaphragm are minimized by creating opposition between two substantially equal forces. There is a slight difference in the opposing forces when the balance is upset and this is sufficient to normally maintain the parts in a central position of equilibrium. Due to the relatively small restoring forces employed the natural or resonant frequency of the armature is quite low and may be kept below the spectrum of sound waves which it is desired to detect. The device is adjustable so that any degree of sensitivity within a cer-

tain range may be obtained and a sufficiently low natural frequency of the vibrating parts may always be insured. The importance of maintaining the natural frequency considerably outside of the range of waves to be received will be apparent when it is considered that the intensity and phase relations of the effects upon a sound receiver change very rapidly with the frequency when approaching the resonant frequency.

With the foregoing considerations in view it has been a primary object of the present invention to construct the device with as few parts as possible. All of the parts that are required, furthermore, are simple in form and hence cheap to manufacture. The assembly is such that the device is compact and rugged and presents very little danger of getting out of order.

Another prominent feature of the present invention is the means adopted for supporting the armature which is vibrated by the sound or similar waves to induce corresponding electrical effects. It is important for the sake of accurate reproduction to so support the armature as to avoid any wobbling motion with respect to the field. Obviously any uncertainty or irregularity in the character of movement of the armature will produce like effects in the induced electric currents which will therefore result in a distorted record or indication. The present invention not only obviates this common cause of distorted reproduction but also combines in the single means for producing this result the function of restoring the armature to its central position of equilibrium.

Other objects and advantages to be derived from the present invention will be apparent from the detailed description which follows and which will be given in connection with the accompanying drawings in which:

Figure 1 is a plan view of the assembly constituting one form of the invention.

Figure 2 is a cross sectional view along a diameter line of Figure 1.

Figure 3 is a view similar to Figure 2 but discloses a modified form of the invention, and

Figure 4 is a similar view showing a further modification of the invention.

Referring now to Figure 2, there is provided a casing 1 formed of any suitable material, preferably a non-conductor of either magnetic lines of force or electrical current, as, for example, bakelite. A flange 2, formed at one end of the casing is adapted to retain certain of the parts in their proper positions while an annular cap 3, which is screw threaded to the casing at its other end, serves to aid in retaining the parts as desired. In the space between the flange 2 and the cap 3 there is provided a series of elements including a diaphragm 4 resting against the flange 2. This diaphragm is formed of good magnetic material, such as laminations of transformer steel. Adjacent the diaphragm there is a thin annular element 5 also formed of magnetic material and adjacent this element is a thicker annular steel ring 6; the latter, however, is not of as great a width in the radial direction as the element 5. Annular members 7, 8, 9, 10 and 11, as well as a diaphragm 12, serve to fill the remaining space between the flange 2 and the cap 3. Of these the members 7, 9 and 11 are substantially like the element 5, while members 8 and 10 are substantially like the heavier annular ring 6. The diaphragm 12 is substantially the same as diaphragm 4 and is preferably made of laminations of transformer steel. Between the members 5 and 7, and directly inside of the ring 6, there is mounted a coil 13, while a corresponding coil 14 is similarly mounted within the ring 10. An armature comprising a member having a knurled head 15 and a shank 16, adapted to support small collars 17 and 18 as well as a disc 19, is mounted between and supported by the diaphragms 4 and 12. It will be apparent that this mode of mounting the armature will serve to permit the desired steady axial movement of the latter and will eliminate the objectionable wobbling which would result in distorted reproduction. A nut 20 is provided on the outside of the diaphragm 4 and this nut cooperates with threads at one end of the shank 16 to hold the parts comprising the armature together. All of the parts of the armature may be formed of magnetic material, if desired, but it is essential only that the annular members 17 and 18, as well as the disc 19, be formed of such material, as, for example, steel.

One of the terminals of each of the coils 13 and 14 is connected to one terminal, such as the negative terminal, of a D. C. source of electricity, such as a battery 21. The remaining terminal of each of the coils is connected to one end of a primary coil of a transformer. Thus the coil 13 may be connected to the primary winding 22, while the coil 14 may be connected to the primary winding 23. The opposite ends of the wind-

ings 22 and 23 are then connected to the positive terminal of the source of electricity. So long as the device is at rest a steady current flowing from the battery 21 through the transformer windings and the coils 13 and 14 will set up magnetic fields around the latter. Preferably the windings of the coils 13 and 14 will be in such sense with relation to each other that the current flowing through them will tend to establish opposed magnetic fields having their polarity oppositely arranged. One of these fields will tend to draw the armature in the direction of the diaphragm 4 and the other will tend to draw the armature in the direction of the diaphragm 12.

In operation the armature through the knurled head 15 will be connected by any suitable means, such as the screw threaded rod illustrated, to a diaphragm 27 which is adapted to receive the sound or similar waves to be detected. As a sound wave strikes this diaphragm it will first move the armature upwardly in Figure 2, thereby carrying the disc 19 closer to the member 7 and further away from the member 9. This will decrease the air gap in the upper magnetic circuit which is comprised by the elements 4, 5, 6, 7, 19 and 18, while the lower magnetic circuit, comprised by the elements 9, 10, 11, 12, 17 and 19, will have its air gap between 9 and 19 increased. With the resulting increase and decrease in the reluctance of the lower and upper magnetic circuits, respectively, the flux will be correspondingly decreased and increased, respectively, in these circuits. Now by the well known laws of magnetism and electricity the increase in flux in the upper circuit will tend to induce a current in the coil 13 opposing the increase and therefore will produce a change in the current in the transformer winding 22 in the direction of the arrow indicated. On the other hand, the decrease in the flux through the lower circuit will induce a current tending to bolster up the already existing current in the coil 14 and transformer winding 23. This change of current, therefore, will be in the direction of the arrow adjacent the winding 23. Variations of the character indicated in the current traversing the windings 22 and 23 will induce corresponding currents in the secondary windings 24 and 25 of the transformers and these currents under the arrangement illustrated will be combined to add their effects upon a galvanometer 26 in the circuit with them.

It will be understood, of course, that the impulses striking the diaphragm 27 will cause alternate up and down movements of the armature so that the currents induced in the transformer windings will be alternately first in the direction indicated and then in the opposite direction.

In connection with the forces acting upon the armature it is to be noted that the dia-

phragms 4 and 12 are of resilient material and therefore tend to maintain the parts in their normal centralized position. Furthermore, the magnetic fields created by the current from source 21 flowing through the coils 13 and 14 will be opposed in their effects upon the armature and under normal conditions will be substantially equal so as to further insure a maintenance of balance. Upward movement of the armature, however, with the resultant increase in flux through the upper magnetic circuit and corresponding decrease in flux through the lower circuit will tend to unbalance the magnetic forces on the armature in such a way as to aid the external impulse. The differential between the magnetic forces thus created in the upward direction will in a measure offset the increased restoring forces of the diaphragms 4 and 12 due to their displacement, but the parts will, of course, be so adjusted that the diaphragms have a slight advantage and will tend to restore the armature to normal. As will be apparent the net restoring force will be relatively small so that the natural frequency of the armature will be below any range of frequencies to be received.

It will be noted that in Figure 2 the source of current 21 is connected in parallel with the two coils 13 and 14. A series arrangement may be adopted, if desired, but for this purpose it is necessary to provide a second set of coils in addition to the coils 13 and 14 surrounding the armature. Figure 3 illustrates a suitable arrangement of circuits for this purpose. Coils 13' and 14', corresponding to coils 13 and 14 of Figure 2, are connected in series with a D. C. source of electricity 21'. A second pair of coils 28 and 29 surrounding the coils 13' and 14', respectively, may then be connected in series with the two primary windings 30 and 31 of a transformer. The remaining portions of the device illustrated in Figure 3 are precisely the same as corresponding portions in Figure 2. Any movement imparted to the armature will vary the flux through the coils 28 and 29, and these may be wound in such relative sense that the currents induced in them will flow in the same direction through the series circuit as, for example, in the direction indicated by the arrow. The combined E. M. F.'s induced in the primary windings 30 and 31 of the transformer will induce a corresponding relatively large E. M. F. in the secondary winding 32 of the transformer and this may be indicated in any suitable way, as by the galvanometer 33. If desired the galvanometer may be placed directly in circuit with the coils 28 and 29 since they carry only induced currents and do not have any constant outside source of current, such as applied to coils 13 and 14. In the event that the induced currents in themselves are not of sufficient strength to effect the desired

results an amplifier of any suitable construction may be employed.

A further modification of the invention is illustrated in Figure 4. In this figure the diaphragms 4 and 12 of Figure 2 are replaced by diaphragms 34 and 35 which are formed of non-magnetic material. The magnetic circuits through the upper and lower coils, therefore, will not include the diaphragms but each will include a second air gap between annular members 5' and 11' and discs 36 and 39, respectively, carried by the armature. Thus in this modified construction two air gaps are provided in each magnetic circuit, the one at the center of the armature being substantially the same as in the first embodiment. However, in order to place the two air gaps for each circuit in series, i. e., in such relation as to increase or decrease both simultaneously, the armature is provided with two discs 37 and 38 at the center corresponding to disc 19 of Figure 2, while a single stationary member 40 cooperates with these discs in a manner similar to the pair of elements 7 and 8 of Figure 2. The terminals of the coils in this modified construction may be connected in parallel with a source of current, as illustrated, or, if desired, two sets of coils similar to those shown in Figure 3 may be provided and a series arrangement of circuits may be adopted.

In other respects the device illustrated in Figure 4 is substantially the same as that illustrated in Figure 2, although this figure illustrates a few of the varied possibilities of changes in construction such as in the form of the closure member for the casing, here shown as a screw threaded annular ring 41 instead of a cap, and in the form of construction of the armature 43 particularly in the means whereby it may be connected to a sound receiving diaphragm. Obviously many other details of construction might be modified within the scope of the invention. Applicant does not desire to limit himself to the particular forms of embodiment disclosed but the invention is to be regarded as limited only by the scope of the claims which follow.

The invention herein described may be manufactured and used by or for the Government of the United States for governmental purposes without the payment to me of any royalty thereon or therefor.

What I claim is:

1. In a sound receiver a plurality of coils, a source of electricity connected with said coils and adapted to produce a plurality of separate magnetic fields around said coils, a rigid, bodily movable armature normally balanced in said magnetic fields, sound responsive means connected with said armature and adapted to reciprocate the latter, resilient members connected with said armature and adapted to restore the latter and means for

indicating the changes in flux of the magnetic fields upon movements of the armature.

2. In a sound receiver a plurality of coils adapted to produce magnetic fields, an armature normally balanced in said fields, diaphragms connected to said armature and adapted to restore the same upon displacement, sound responsive means for reciprocating said armature, a magnetic circuit for each of said coils including an annular member, and means carried by said armature in spaced relation with said annular members and adapted to form air gaps therewith in said magnetic circuits, said members and means being relatively movable upon movements of said armature.

3. In a device for converting mechanical vibrations into electrical energy, a plurality of coils, a plurality of separate magnetic circuits adapted to carry variable flux through said coils, each circuit being related to a particular coil, said circuits being each provided with an air gap, and means responsive to said mechanical vibrations for increasing the air gap in one of said circuits and simultaneously decreasing the air gap in another of said circuits.

4. In a device of the class described an armature, coils surrounding said armature, means adapted to establish a plurality of separate opposed magnetic fields acting on said armature, each of said fields being related to one of said coils, means carried by said armature adapted to vary the flux in said magnetic fields, and means for indicating the combined variation in flux in said fields.

5.. In a device of the class described a bodily movable armature, diaphragms for supporting the armature at its ends, means for establishing a plurality of separate magnetic fields providing opposed magnetic forces on said armature, elements of magnetic material normally separated by an air gap and relatively movable to vary the air gap upon movements of the armature, said elements being in the circuits of said magnetic fields, and electrical conductors in the fields whose fluxes are thus varied.

6. In a device of the class described a casing, means within said casing for establishing a plurality of separate magnetic fields, an armature movable longitudinally in said fields and forming a part of the magnetic circuits, magnetic conductors carried respectively by said armature and said casing adapted to form an air gap in each circuit, and means for detecting the variations in flux through said circuits due to varying the air gaps upon movements of the armature.

7. In a device of the class described an armature, diaphragms for supporting the armature at its ends, said diaphragms being formed of non-magnetic material, means for establishing a plurality of separate magnetic

fields providing opposed magnetic forces on said armature, elements of magnetic material normally separated by an air gap and relatively movable to vary the air gap upon movement of the armature, said elements being in the circuits of said magnetic fields, and electrical conductors in the fields whose fluxes are thus varied.

8. In a device of the class described a casing, means within said casing for establishing a plurality of magnetic fields, an armature movable longitudinally in said fields and forming a part of the magnetic circuits, magnetic conductors carried respectively by said armature and said casing adapted to form a plurality of air gaps in each of said circuits, said air gaps in each circuit being arranged in series so as to vary in the same sense upon movements of the armature, and means for detecting the resulting variations in flux through said circuits.
